UNITED STATES PATENT OFFICE.

WILLIAM D. REID, OF BROOKLYN, NEW YORK.

CLEANING METHOD AND MEANS.

Application filed April 14, 1927. Serial No. 183,824.

This invention relates to improvements in cleaning methods and means, and more particularly to the removal of ink and like material from non-absorptive surfaces, such, 5 for instance, as to the periodic cleaning of typewriter type.

An object of the invention is to provide simple manual means for quickly and conveniently cleaning the type of typewriters 10 from deposits of ink left by the ribbon during the use of the typewriter. An occasional use of this invention keeps the type-faces forever perfectly clean.

Another object of the invention is to provide a novel method of any such removal 15 or cleaning by the process of absorption, rather than the usual combined process of dissolving and brushing away, thus eliminating also any possible damage from abrasion.

20 A further object is to provide such a means which can be thus used inter-changeably on all well-known makes of typewriters.

Yet another object is to provide such a device with means for conveniently and economically replacing the absorbing material 25 with fresh material when it has become clogged with the absorbed deposit.

Finally, an object is to provide a convenient and cheap cover means for such a device 30 that is quickly applied and prevents the absorbing material soiling or being soiled.

Other objects will be apparent as the description proceeds.

All these objects are attained by the methods hereinafter described, and the means illustrated in the accompanying drawing, in 35 which—

Figure 1 is a perspective view of the complete cleaning device, adapted for use with 40 Underwood and Remington typewriters; Fig. 2, a partial cross-sectional view of the same device as Fig. 1, but adapted for use with L. C. Smith and Royal typewriters; Fig. 3, a perspective view of the strip of absorbing material which is replaceably applied 45 to the device; Fig. 4, a side elevation and partial sectional view of the form of device shown in Fig. 1 and containing the protective cover means in which it is sold and retained 50 when not in use; and Fig. 5, a side view of the shaft or pin on which the roller revolves in the form shown in Fig. 1.

Similar numerals refer to similar parts 55 throughout the several views.

Long experimentation by the inventor has shown that by far the best means of removing

accumulations of ink from the type-faces on typewriters, or like material from like surfaces, is not, for instance, by the process of dissolving and brushing away, which involves abrasion, but rather by a process of absorption.

This conception of a new method of cleaning the type by the process of absorption then necessitated further experimenting to 65 develop a substance which would be effective and would cleanly remove all the ink without leaving behind any of its own substance. After considerable research, a substance, having as a base a material known to the trade 70 as "kneaded rubber", was found to work most satisfactorily. This material must be of the proper consistency and is procurable from the large rubber companies, and includes ingredients now well-known in the 75 arts. The peculiar property which it possesses of completely absorbing ink from a hard surface without at the same time leaving behind a deposit of its own, is the quality 80 used in this invention.

While a ball of this material, properly prepared, might be used in the fingers of the operator to clean the type by being positioned successively over the various portions of type 85 on the average typewriter, the inventor has devised a very novel and convenient means for accomplishing this in a much more satisfactory and efficient manner.

This device consists of a handle 1, Fig. 1, on one end of which is rotatably mounted a 90 roller 2, revolving around a shaft or pin 3. The surface of this roller 2 is composed of kneaded rubber, or like absorbing material, 4.

The roller 2 is shown in one form in cross-section in Fig. 2. It here consists of two side 95 plates, or discs, 5, usually of metal, separated by a cylindrical core 6, preferably of wood, through all three of which there has been punched or drilled an aligned concentric hole, slightly larger than the diameter of the pin 100 on which it revolves. This pin is of the shape of part numbered 3 in Figs. 1 and 5, when the device is to be used on Underwood and Remington typewriters. When, however, it is to be used on Royal and L. C. Smith typewriters, in view of a different arrangement in the exposure of the type, the form shown in Fig. 105 2 has been devised, all the parts of this form being common to that of Fig. 1 with the exception of the pin 3, which is here replaced by pin 7, as shown. This pin has an essentially 110 right angle turn at the top, so that

the roller rotates in an approximately horizontal plane to the handle, instead of in a lateral plane as in Fig. 1. There is also a slight offset in the shank of the pin to permit the roller to rotate freely and without jamming in the necessarily slightly-rounded corner where the pin is bent; this method is used to reduce cost and without resorting to forming an expensive shoulder on the pin or other means of accomplishment.

10 The kneaded rubber is preferably applied to the roller in the form of a strip, as shown in cross-section at 4, Fig. 2, and in perspective in Fig. 3.

15 The pins are, of course, headed to retain the roller.

16 The assembly of the form shown in Fig. 1 is made by simply placing pin 3 through the hole of roller 2 and hammering it into the 20 handle 1, or otherwise securing it, allowing enough clearance between the respective sides of the roller, and the head of the pin and the end of the handle, to permit free rotation of the roller. In assembling the forms shown 25 in Fig. 2, however, the pin 7 is first affixed to handle 1, the roller is then positioned over the bend of the pin, and finally, the pin is headed as shown, and in such manner, again, as to permit free rotation of the roller.

30 These devices are preferably sold wrapped in a container of the form shown in Fig. 4, which consists essentially of a cup-shaped cardboard cover 8, usually pressed from a flat sheet, along the edge of which is fastened 35 a strip of relatively thin paper 9, which is folded or bunched up around the top of the handle, in manner as shown, to completely encase the cleaning roller. This covering not only protects the device in shipment, but is 40 also useful in preventing smearing of desk drawers, and so forth, when in use, as well as keeping out the air preventing the material from drying up. With this last in mind, the container should be waxed or otherwise 45 made impervious to moisture.

46 The strips of absorbing material can be sold in the form shown in Fig. 3 to replace the worn out and ink-clogged material on the device, which, however, has been found to work 50 satisfactorily for a long period of months before such replacement is necessary. These strips of material are conveniently sold in envelopes, and for a price that is only a fraction of the total cost of the device, which itself 55 is comparatively small. This will establish a repeat business, which is so desirable from a selling angle.

56 In operation, the typist merely takes the device in his or her hand and places the 60 gummed surface of the roller on the type-

writer type, the handle extending laterally of their assembly, and then rolls the roller across the surface of all the type, down one side and up the other, and so repeating a number of times until the surface of the 65 type is clean and shiny, and all of the ink has been absorbed into the rubber material on the roller face. The kneaded rubber blots this into itself, and in time creeps around to absorb it and present a more or less fresh 70 surface to absorb more ink. As stated, this process may be repeated scores of times before the efficiency of the device is appreciably impaired.

75 It is to be understood that the present disclosure is for the purpose of illustration only, and that the invention is not limited thereto. To those skilled in the art, many modifications of the invention, whether of the device, method, or composition of material, 80 will be readily apparent, and it will also be obvious to such skilled persons that part of the invention may be used without other parts thereof, many such combinations of the parts and steps readily suggesting themselves. Therefore, it should be, and is to be distinctly understood that for a definition 85 of the limitations of the invention, reference must be had to the appended claims.

Having now described the invention, what 90 is new, and for which Letters Patent of the United States is desired, is:

1. A device for cleaning typewriter type, including a handle and kneadable absorption means rotatably mounted on the handle to 95 be rolled across the surface of the type.

2. In combination, a handle, a pin in the handle, and a roller rotatably mounted on the pin to rotate in a plane at right angles to the handle, and, its surface being covered with 100 ink absorbing kneadable material.

3. In combination, a concentrically bored cylindrical member, a disc on each side of said member and somewhat larger in diameter, a strip of non-hardening kneadable material between the discs and around the periphery of the member, the assemblage being 105 adapted to be rotatably mounted.

4. In combination, a handle, a disc having a central hole and a peripheral groove, a 110 headed pin extending through the hole and connected with the handle rotatably mounting the disk on the handle, and an endless strip of non-hardening non-adhesive kneadable material along said groove.

115 Signed at New York, in the county of New York and State of New York this 12th day of April, A. D. 1927.

WILLIAM D. REID.
